UNITED STATES PATENT OFFICE.

WILLIAM TWEEDDALE, OF BROOKLYN, ASSIGNOR TO THE J. L. MOTT IRON WORKS, OF NEW YORK, N. Y.

DESIGN FOR A FIRE-PLACE.

SPECIFICATION forming part of Design No. 13,310, dated September 19, 1882.

Application filed August 11, 1882. Term of patent 7 years.

To all whom it may concern:

Be it known that I, WILLIAM TWEEDDALE, of Brooklyn, in the State of New York, have invented a Design for Fire-Places, of which

5 the following is a specification.

This design relates to the appearance of the fire-place frame and the fender, in which stems, leaflets, and sunflower ornaments conspire to produce a harmonious and artistic effect.

10 The fender has bars *a* *b* and base *c*, with vertical bars *e*, forming panels and open-work. The ornamental rods at *d* are between *a* and *b*. The star-shaped flowers and leaves *f* are also between the bars *a* and *b*, and below these the 15 catharine-wheel ornament *g*. Between the ornaments *g* *g* there are the stem, leaflet, and sunflower ornaments *h*, and the sections of the fender containing these respective ornaments are arranged as shown.

15 The grate-frame has astragal borders *k* and surface ornaments of stems, leaflets, and sunflowers, as represented at *l*.

The andirons have globular top ornaments, *n*, urn-shaped bodies *m*, and scroll and star 20 ornaments at *o*.

The fender-piece, frame, and andirons compose one harmonious design for a fire-place, the respective parts being ornamented with reference to the artistic effect of the whole.

I claim as my invention—

1. The design of the fender-piece, composed of the bars *a* *b* *e*, base *c*, rods *d*, catharine-wheel *g*, star-flowers and leaflets *f*, stems, leaflets, and flowers *h*, substantially as represented. 30

2. The design of the fire-place frame, composed of the borders, leaflet, flower, and stem ornaments, substantially as represented. 35

3. The design of the andirons, composed of the ball, the urn, the scroll, and star ornaments, as represented. 40

Signed by me this 7th day of August, A. D. 1882.

WILLIAM TWEEDDALE.
